UNITED STATES PATENT OFFICE.

CHARLES MUNZNER, OF CHICAGO, ILLINOIS, ASSIGNOR TO AMERICAN STOVE COMPANY,
OF ST. LOUIS, MISSOURI, A CORPORATION OF NEW JERSEY.

WICK-HOLDER.

1,254,342.

Specification of Letters Patent. Patented Jan. 22, 1918.

Application filed April 28, 1917. Serial No. 165,160.

To all whom it may concern:

Be it known that I, CHARLES MUNZNER, a citizen of the United States, residing at Chicago, in the county of Cook and State 5 of Illinois, have invented certain new and useful Improvements in Wick-Holders, of which the following is a specification, reference being had therein to the accompanying drawing.

10 My invention relates to improvements in wick holders, and its object is to provide a wick holder which will detachably and adjustably hold the wick in the wick holder in a simple and efficient manner.

15 In the accompanying drawings—

Figure 1 is a sectional view of my improved wick holder in position in the wick tubes and carrying the wick.

20 Fig. 2 is a partial sectional view of my improved wick holder, shown on an exaggerated scale.

25 Fig. 3 is a perspective view of my improved wick holder looking at it from the under side, the top being partially broken away and the wick in position in the holder.

Fig. 4 is a fragmentary sectional view showing a slight modification in the bending of the lower end of the holder.

30 Referring now to the drawings, 1 is the outer wall and 2 the inner wall of an ordinary wick tube of an oil stove.

35 My improved wick holder comprises the usual perforated cylinder 3, the perforations being utilized as means for raising and lowering the holder by a toothed wheel (not shown) in a manner well understood by those skilled in the art, and the perforations also serve as openings through which the oil in the wick tube may readily reach the wick.

40 My improved wick holder has its lower end turned inward, as shown at 4, and extended upward into an annular flange 5, the perforations 4 and 5 forming with the adjacent wall of the perforated cylinder 3, a 45 U-shaped lower end on the holder in which the lower end of the wick 6 may enter when the wick is new and first applied to the holder. A plurality of elongated upwardly extending arms 7 project from the flange 5,

50 and these arms are preferably integral with the flange. The upper ends of these arms are pointed and turned inward, as shown at 8, forming points which are forced into the wick when the holder carrying the wick is placed between the walls 1 and 2 of the wick

tube. When the wick is to be placed in the holder, the arms 7 are normally in the position shown in Fig. 2, with the pointed ends or prongs 8 out of engagement with the wick. The wick being positioned in the 60 holder, the prongs may be first forced into the wick by the hand, and as the wick holder and the arms are of a non-spring or ductile metal, the arms will stay with the prongs 65

naturally embedded in the wick. Even 70 though the metal of which the holder and arms are formed is of a soft or ductile metal, the long arms naturally have a little inward spring, or a slight tendency to return to the positions to which they are bent, before the 75 wick is placed in the holder. However, when the holder is pushed down in the wick tube, the inner wall of the tube engages the arms 7 and will force them outward and hold them with the pointed ends or prongs 8 embedded in the wick. As long as the 80 holder is within the wick tube as it is moved up and down by the raising device (not shown), the arms are held outward and the prongs in engagement with the wick.

85 The forming of the annular flange or wall 5 at the lower end of the holder, forms a substantial wall from which the arms 7 project, and a substantial support for the arms.

90 While the U-shaped portion formed by the bent part 4 and flange 5 may be in some cases made sufficiently wide to receive the lower end of the wick, as in Fig. 4, preferably the space between the wall 5 and the cylinder 3 is not sufficiently wide to conveniently receive the frayed end 9 of the wick, as shown in Fig. 2. In fact, this flange 95 is not primarily for the purpose of forming a U-shaped pocket for the lower end of the wick, though it may be used for that purpose. The primary object of the flange is to form a substantial support for the arms 7 and from which they project, and to also form a stiff lower end for the holder and cause it to maintain its proper circular form.

100 By means of this improvement the new wicks may be applied to the holder and will not necessitate a new holder when a new wick is necessary, and it also enables the wick to be adjusted vertically after it has been sufficiently burned to require vertical adjustment for subsequent use.

105 I am aware that it is not new to provide a holder with prongs adapted to be forced in the wick whereby new wicks may be ap-

110

plied to the holder, and whereby the wick is vertically adjustable, but so far as I am aware, it has not been accomplished in the way here shown and according to my present specific improvement.

Having thus described my invention, what I claim and desire to secure by Letters Patent is—

An improved wick holder comprising a 10 perforated cylinder having its lower end bent inwardly and upwardly to form an inner annular upwardly extending flange, and

a plurality of upwardly extending integral elongated narrow arms carried by the flange and having their upper ends pointed and turned outwardly forming prongs adapted to enter a wick and held therein by the inner wall of a wick tube.

In testimony whereof I hereunto affix my signature in the presence of two witnesses. 20

CHARLES MUNZNER.
